HENRY H. BLAKE, OF PITTSBURGH, PENNSYLVANIA, ASSIGNOR TO BLAKE CRUSHER AND PULVERIZER COMPANY, OF PITTSBURGH, PENNSYLVANIA, A CORPORATION OF PENNSYLVANIA.

BOTTOM CONSTRUCTION FOR FURNACES.

1,104,402.

Specification of Letters Patent. Patented July 21, 1914.

Application filed June 30, 1911. Serial No. 636,294.

To all whom it may concern:

Be it known that I, HENRY H. BLAKE, a citizen of the United States, and residing in the city of Pittsburgh, in the county of Allegheny and State of Pennsylvania, have invented or discovered new and useful Improvements in Bottom Construction for Furnaces, of which the following is a specification.

10 My invention consists of a new and improved construction for the bottom or floor of a furnace or other combustion chamber. It is especially applicable to combustion chambers wherein pulverized fuel is introduced under pressure in such a manner that the flame impacts against and reverberates from the floor of the combustion chamber. A fire-brick floor exposed to such treatment quickly disintegrates and the products of 15 combustion precipitated thereon adhere thereto and cannot be removed without injury to the floor structure.

Where sufficient space is available beneath the combustion chamber a deep bed of ash 20 may be maintained and kept at proper level to receive and reverberate the flame but frequently there is not space for such a bed of ash and some other floor structure requiring less room must be substituted. This is especially true in the case of light draft river 25 steamers, locomotives, and in boiler rooms where there is no considerable excavation under the boilers.

By the use of my invention all the advantages of the deep ash-bed are obtained by 30 the use of a shallow layer of ashes, at much less cost of installation, and under circumstances which prohibit the use of the deep bed. For this purpose I install in the bottom of the combustion chamber, as in the ash-pit of the ordinary furnace, and above 35 the floor thereof, a series or system of water pipes or other cooling agents, preferably connected to a common supply, and which 40 may, if desired, be used as a preliminary heater for the boiler water. These pipes are spaced apart preferably for a distance somewhat greater than their diameter, and inclined downwardly toward the front wall of 45 the combustion chamber where a door is provided for the removal of the surplus accumulations of ash.

The space between the pipes and the floor

of the chamber becomes filled with ashes which form a permanent bed sufficiently 55 chilled by the pipes to prevent injury to the floor. Above the pipes a layer of ashes is formed by accumulation which receives the impact of the flame and reverberates the same upwardly. The top layer remains at 60 a high temperature so that the particles of combustible material which may be deposited thereon from the flame are consumed without loss of heat value. The top layer is maintained at the proper level by 65 removals from time to time through the ash door and a tool may be introduced occasionally to smooth the top of said layer. The products of combustion will not adhere to the pipes but may be readily removed when desired.

In the accompanying drawings, Figure 1 is a vertical section of a boiler furnace fitted with my invention, and Fig. 2 is a detail plan of the pipe system recommended for 75 use in connection with my invention.

The following is a detailed description of the drawings.

A is a boiler; B is the furnace or combustion chamber; C is the bridge wall; D 80 the arch, and E the front wall.

F represents the fuel distributor introducing pulverized fuel from above. The fuel is ignited by the heat of the furnace and forms a very hot flame G which impacts 85 against the bottom of the combustion chamber and is reverberated thereby.

1 is the floor or bottom of the combustion chamber formed of any suitable material, such as fire-brick. Spaced above the floor 1 90 is a cooling device, shown as a system of water pipes 2-2 which are preferably inclined downwardly toward the front wall E and connected to a common header 3 which is of greater diameter than pipes 2-2. 95 Water is supplied to header 3 and through it to pipes 2-2 to keep down the temperature of said pipes.

I find it convenient to use the pipes 2-2 for the preliminary heating of the boiler 100 water. In such case I may admit the water to header 3 through a pipe 4, preferably of greater diameter than pipes 2-2, and connected to the water supply pipe 5. The ends of the pipes 2-2 are connected by unions 105 6-6. The other end of header 3 is connect-

ed by pipe 7 to the boiler for the purpose of feeding water, previously heated in the water cooled pipes to the boiler.

The ashes dropping down through pipes 2—2 form a permanent bed 8 on the floor 1 extending up to the pipes 2—2. This bed 8 protects the floor 1 against excessive heat, being kept at moderate temperature by the pipes 2—2. Above the pipes 2—2 a second 10 bed of ash, 9, is allowed to accumulate which receives the impact of and reverberates the flame G.

A door or opening 10 is formed in the front wall E at the foot of pipes 2—2 for 15 the occasional removal of the surplus ashes as they accumulate, and the top of bed 9 may be kept level by means of a tool inserted through a door 11 in the wall E above the door 10. The inclination of the pipes 20 2—2 facilitates the removal of surplus ashes through the door 10.

It is evident that my invention provides a floor construction for the purpose described that will not disintegrate, is self-renewing, requires no more space than the ordinary ash-pit, and completely protects the floor of the combustion chamber.

What I desire to claim is—

1. Cooling means especially adapted for 30 shallow combustion-chambers of furnaces, comprising, in combination with the combustion-chamber, a series of connected, substantially horizontally arranged, imperfo-

rate pipes disposed near the bottom of said combustion-chamber, means for circulating water through said pipes, and a bed of material disposed between said pipes and the bottom of said combustion-chamber, and serving as a non-conductor of heat. 35

2. Cooling means especially adapted for 40 shallow combustion-chambers of furnaces, comprising, in combination with the combustion-chamber, a series of connected pipes disposed near the bottom of said combustion-chamber and inclined from the rear to 45 the front of said combustion-chamber, means for circulating water therethrough, and a bed of material disposed between said pipes and the bottom of said combustion-chamber, and serving as a non-conductor of heat. 50

3. In a furnace, a boiler, connected pipes disposed near the bottom of the combustion-chamber of the furnace, a connection between said pipes and said boiler, affording communication therebetween, means for circulating water through said pipes and a bed of material disposed between said pipes and the bottom of said combustion-chamber, and serving as a non-conductor of heat. 55

Signed at Pittsburgh, Penn., this 24th 60 day of June 1911.

HENRY H. BLAKE
